UNITED STATES PATENT OFFICE.

JAAKKO AALTO, OF MILLINOCKET, MAINE.

SYSTEM OF AIR COMPRESSION.

Application filed April 9, 1921. Serial No. 460,133.

To all whom it may concern:

Be it known that I, JAAKKO AALTO, a citizen of the Republic of Finland, residing at Millinocket, in the county of Penobscot and 5 State of Maine, have invented certain new and useful Improvements in System of Air Compression, of which the following is a specification.

The invention relates to improvements in 10 compressors generally, and more particularly to a dual system of air compression for the storing up of a supply of compressed air for subsequent use.

The principal object of the invention is to 15 provide for a system of air compression, and one embodying the use of a pair of oppositely disposed compressors, each having means associated therewith to greatly increase the volume of air to be drawn into 20 the compression cylinders thereof, and to otherwise increase the efficiency of the apparatus as a whole over known types of the same.

A further object of the invention is to 25 provide for an air compression apparatus of the character mentioned, and one involving a pair of power driven intake devices or impellers whereby air is forcibly drawn from atmosphere, and is partially compressed during 30 its passage into the compression cylinders, such partial compression of the air acting to increase the density or volume of air admitted to the cylinders during the suction stroke of the pistons of the same.

35 With the foregoing and other objects in view, the invention resides in the certain novel and useful construction and arrangement of parts as will be hereinafter more fully described, set forth in the appended 40 claims, and illustrated in the accompanying drawing, in which:

Figure 1 is a vertical sectional view of an apparatus in accordance with this invention, and

45 Figure 2 is an end view of one of the impellers.

Referring to the drawing, the numerals 10 and 11 designate a pair of opposed compression cylinders open at their inner adjacent 50 ends to receive within the same complementary piston heads 12 and 13, which are to be reciprocated therein through the medium of pitmans or piston rods 14 and 15, respectively. These pitmans or piston rods 14 and 55 15 are pivotally connected at points centrally of the outer ends of the piston heads

12 and 13, as at 16 and 17, and have a common pivot connection, as at 18, to a drive wheel 19, which is in the form of a beveled gear mounted on a shaft 19' and arranged in mesh with a bevel pinion 20, mounted on a power shaft 21. The gear wheel 19 is also in mesh with a bevelled pinion 20', carried by a transmission shaft 21' which is disposed in longitudinal alignment with respect to the 60 shaft 21. The shafts 21 and 21' extend between the opposed ends of the cylinders 10 and 11 in a plane at right angles to the longitudinal centers thereof. Each of the cylinders 10 and 11 have their closed end walls 70 provided with valved inlet ports 22 and 23 and valved outlet ports 24 and 25, respectively, and connecting these several valved ports are inlet and outlet pipes 26 and 27 and 28 and 29, respectively.

75 Each inlet pipe 26, 27, is an element of a pumping mechanism and each of said mechanisms consists of a flanged hemispherical outlet head 30 to which the pipe 26 or 27 is connected. Each of the said mechanisms 80 further includes a rotatable hollow cylindrical body 32, open at each end and having one end opening into and operating against the outlet head 30, the latter being stationary and fixedly secured to a bearing 33'. 85 Mounted in the bearing 33' and also in a bearing 33, is the cylindrical body 32. Mounted in the rotatable body 32, as well as being carried therewith, is a spiral pumping element or device 31. The body 32 is rotated through the medium of a pulley 34 carried on or keyed to the sleeve or casing 32 at a point intermediate its end, and between the bearing blocks 33 and 33'. Belts 35, 35' are provided for driving the impellers, the former leads from the pulley 36 on the shaft 21 and the latter from the pulley 36' on the shaft 21'. The belts 35, 35' are connected to the pulleys 34.

90 Connected to the outlet pipes 28, 29, are storage tanks 37, 37' respectively and each of said tanks is provided with a valved inlet 95 38 associated with its respective outlet pipe from the compressor. Each of the tanks 37, 37', is provided with an outlet 39, with which 100 cooperates a safety valve 39', which is carried by a lever arm 40, intermediate the ends of the latter. The valves 39' are pivoted to the lever arms 40. The lever arms 40 are pivoted to the storage tanks, as at 41, and 105 each of said lever arms 40, has its outer free end provided with an adjustable weight 42,

capable of being adjusted along the outer end of the lever arm 40, for the purpose of counterbalancing the weight of the outlet valves.

5 In the operation of the system of air compression involved in the use of the apparatus thus provided, suitable power is applied to the shaft 21, and air is alternately drawn into the cylinders 10 and 11, one cylinder 10 being on its compression stroke when the other is on its suction or intake stroke. Upon the starting up of the rotation of the power shaft 21, the belts 35, 35' are driven from the pulleys 36, 36' for the rotation of 15 the spiral impellers 31, in a direction to draw in the air from the surrounding atmosphere and force the same in the cylinders during the suction stroke of the pistons therein, as aforesaid. On the compression stroke of the 20 pistons, the air is compressed through the valved outlet openings 24 and 25, and is discharged, through the outlet pipes 28 and 29 leading therefrom, into the tanks 37, 37'. The safety-valves 39' are properly counter- 25 balanced by the adjustment of the weights 42 in the lever arm 40, so as to open under pressures exceeding that predetermined by the setting of the same, so that all danger from over compression is eliminated. The 30 action of the spiral impellers or intake devices 31 is such as to greatly increase the volume or density of the air passing through the cylinders as compared to that which would otherwise be drawn into the latter 35 merely under the suction stroke of the pistons, and, in addition to increasing the volume, these impellers or devices also effect a partial compression of the air for increasing the density thereof in its passage through 40 the inlet pipes 26 and 27 to the cylinders, with the result that a larger body or volume of air is sucked in each cylinder during the non-compression stroke of the pistons.

From the foregoing, it will be readily apparent that the apparatus provides for a very efficient system of air compression, and one that is capable of compressing and storing up a maximum amount of air from an apparatus of a relatively small capacity,

such as results in extremely low cost in 50 manufacture, installation and operation of the apparatus, since the provision of the devices for increasing the density, or otherwise partially compressing the air to increase the volume admitted to the compressor cylinders is in effect a corresponding 55 increase in the capacity of the latter.

Having thus fully described the invention, what is claimed, is:—

1. An apparatus for the purpose set forth 60 comprising bearing means, a hemispherical stationary outlet head fixed thereto and provided with a discharge pipe, a rotatable hollow cylindrical body mounted in said means, open at each end and having one end opening into and bearing against said outlet head, a pumping device of spiral form arranged within and carried with said element, and operating means for said element.

2. An apparatus for the purpose set forth 70 comprising a pair of spaced bearings, a hollow hemispherical outlet head fixed to one of said bearings and provided with a discharge pipe, a rotatable hollow cylindrical body mounted in said bearings and open at each 75 end, said body opening at one end into and bearing against said head, means engaging with said body between said bearings for rotating said body, and a pumping element arranged within and carried with said body so during the operation of the latter.

3. An apparatus for the purpose set forth 85 comprising a pair of spaced bearings, a hollow hemispherical outlet head fixed to one of said bearings and provided with a discharge pipe, a rotatable hollow cylindrical body mounted in said bearings and open at each 90 end, said body opening at one end into and bearing against said head, means engaging with said body between said bearings for rotating said body, and a pumping element of spiral form arranged within and extending from one end to the other of said body and further carried with the body during 95 the operation thereof.

In testimony whereof I affix my signature hereto.

JAAKKO AALTO.
